UNITED STATES PATENT OFFICE.

GEORGE P. WIGGINTON, OF KALAMAZOO, MICHIGAN, ASSIGNOR TO KALAMAZOO
LOOSE LEAF BINDER CO., OF KALAMAZOO, MICHIGAN.

TEMPORARY BINDER.

Application filed June 16, 1921. Serial No. 475,000.

To all whom it may concern:

Be it known that I, GEORGE P. WIGGINTON, a citizen of the United States, residing at the city and county of Kalamazoo, State of Michigan, have invented certain new and useful Improvements in Temporary Binders, of which the following is a specification.

This invention relates to improvements in temporary binders.

10 The main objects of this invention are:

First, to provide an improved temporary binder or loose sheet holder which is well adapted for holding loose sheets, circulars and the like, and one in which the sheets 15 are securely bound when it is desired to handle the same as a binder and at the same time may be quickly removed or inserted.

Second, to provide an improved binder for loose sheets in which there are no exposed metal parts.

20 Further objects, and objects relating to structural details, will definitely appear from the detailed description to follow.

I accomplish the objects of my invention 25 by the devices and means described in the following specification. The invention is clearly defined and pointed out in the claims.

A structure which is a preferred embodiment of my invention is clearly illustrated 30 in the accompanying drawing, forming a part of this application, in which:

Fig. I is a perspective view of a binder embodying the features of my invention.

35 Fig. II is a sectional view on a line corresponding to line 2—2 of Fig. I, parts being shown in full lines for convenience in illustration.

Fig. III is a detail section on a line corresponding to line 3—3 of Fig. II.

40 Fig. IV is a perspective view of the binding bars removed from the covers.

Fig. V is a perspective view of the sheet body removed from the binder, the binding posts being removed therewith or being in the sheet body.

45 Fig. VI is a sectional view corresponding to that of Fig. II, in which the heads of the posts are arranged on the outer side 50 of the binding flaps instead of on the inside thereof as shown in Fig. II.

In the drawing similar reference characters refer to similar parts throughout the several views, and the sectional views are

taken looking in the direction of the little 55 arrows at the ends of the section lines.

Referring to the drawing, the covers 1, 1 are, in the embodiment illustrated, connected by the flexible back 2. The covers have binding flaps 3 secured within the 60 same, the flaps being preferably provided with fly leaf extensions 4 as shown in the drawing.

The sheets 5 are provided with holes 6 adapted to receive the posts 7 having disk-like heads 8 thereon adapted to engage the sheet body or engage the binding flaps when arranged on the outer side thereof, as shown in Fig. VI. The posts also have studs 9 projecting beyond the heads 8. The binding bars 10 and 11 are adapted to be disposed on the outer side of the binding flaps and are provided with holes 12 aligned with the holes in the binding flaps to receive the studs 9.

75 The binding bars are detachably connected and clamped upon the binding flaps by means of the coupling members 13 which are pivoted in the longitudinal slots 14 of the lower binding bar 10 and adapted to 80 engage the slots 15 of the upper binding bar. These coupling members are preferably formed of threaded sections, so that they may be adjusted to correspond with the sheet body.

85 In using my improved binder the heads 8 of the posts may be disposed on the inner side of the fly leaf on the binding flaps as shown in Fig. II or on the outside thereof as shown in Fig. VI. To a considerable extent this is a matter of taste or convenience. If it is desired to handle the sheet body as a unit outside of the binder the posts should be disposed with their heads between the binding flaps and the 95 outer sheets and, when so arranged, it is only necessary to disengage the binding bars and the entire sheet body may be lifted out. It will be noted that the binding posts are of such length that they interlap in the 100 body of the sheets,—see Figs. II and VI.

My improved binder is very compact and attractive in appearance and may be readily adjusted for the insertion or removal of the sheets or leaves. When bound the 105 sheets are securely retained and no metal parts are exposed.

Having thus described my invention,

what I claim as new and desire to secure by Letters Patent, is:

1. In a temporary binder, the combination with sheets provided with holes adapted to receive posts, of covers, binding flaps within said covers having holes therein aligned with the holes of the sheets, posts engaging said holes in said sheets and provided with heads and with outwardly projecting studs, said posts being adapted to be disposed with their heads between the binding flaps and the sheets or on the outer sides of the binding flaps, the posts being arranged from both sides of the sheet body and overlapping therein, and detachable binding bars disposed on the outer sides of said binding flaps and provided with holes receiving said studs, said binding bars being provided at their ends with disengageable and extensible coupling means.
2. In a temporary binder, the combination with sheets provided with holes adapted to receive posts, of covers, binding flaps within said covers having holes therein aligned with the holes of the sheets, posts engaging said holes in said sheets and provided with heads and with outwardly projecting studs, and detachable binding bars disposed on the outer sides of said binding flaps and provided with holes for receiving said studs, said binding bars being provided at their ends with disengageable and extensible coupling means.
3. In a temporary binder, the combination with sheets provided with holes adapted to receive posts, of covers, binding flaps within said covers having holes therein aligned with the holes of the sheets, posts engaging said holes in said sheets and provided with heads and with outwardly projecting studs, said posts being adapted to be disposed with their heads between the binding flaps and the sheets or on the outer sides of the binding flaps, the posts being arranged from both sides of the sheet body and overlapping therein, and binding bars disposed on the outer sides of said binding flaps and provided with holes for receiving said studs and with coupling means.
4. In a temporary binder, the combination with sheets provided with holes adapted to receive posts, of covers, binding flaps within said covers having holes therein aligned with the holes of the sheets, posts engaging said holes in said sheets and provided with heads and with outwardly projecting studs, and binding bars disposed on the outer sides of said binding flaps and provided with holes for receiving said studs and with coupling means.
5. In a temporary binder, the combination with sheets provided with holes adapted to receive posts, of covers connected by a flexible back, binding flaps within said covers

having holes therein aligned with the holes of the sheets, posts engaging said holes in said sheets and provided with heads and with outwardly projecting studs, said posts being adapted to be disposed with their heads between the binding flaps and the sheets or on the outer sides of the binding flaps, the posts being arranged from both sides of the sheet body and overlapping therein, and binding bars disposed on the outer sides of said binding flaps and provided with holes for receiving said studs and with coupling means.

6. In a temporary binder, the combination of the covers provided with binding flaps having holes therein, sheet and flap engaging posts provided with heads and with outwardly projecting studs, said posts being adapted to be disposed with their heads between the binding flaps and the sheets or on the outer sides of the binding flaps, and detachable binding bars disposed on the outer sides of said binding flaps and provided with holes for receiving said studs, said binding bars being provided at their ends with disengageable and extensible coupling means.

7. In a temporary binder, the combination of the covers provided with binding flaps having holes therein, sheet and flap engaging posts provided with heads and with outwardly projecting studs, and detachable binding bars disposed on the outer sides of said binding flaps and provided with holes for receiving said studs, said binding bars being provided at their ends with disengageable and extensible coupling means.

8. In a temporary binder, the combination of the covers provided with binding flaps having holes therein, sheet and flap engaging posts provided with heads and with outwardly projecting studs, said posts being adapted to be disposed with their heads between the binding flaps and the sheets or on the outer sides of the binding flaps, and binding bars disposed on the outer sides of said binding flaps and provided with holes for receiving said studs.

9. In a temporary binder, the combination of the covers provided with binding flaps having holes therein, sheet and flap engaging posts provided with heads and with outwardly projecting studs, and binding bars disposed on the outer sides of said binding flaps and provided with holes for receiving said studs.

In witness whereof I have hereunto set my hand and seal in the presence of two witnesses.

GEORGE P. WIGGINTON. [L. S.]
